UNITED STATES PATENT OFFICE.

ROBERT W. WHITEHURST, OF NORFOLK, VA., ASSIGNOR OF TWO-THIRDS TO
AURELIUS WRENN AND McDONALD L. WRENN, BOTH OF SAME PLACE.

PLOW.

SPECIFICATION forming part of Letters Patent No. 319,872, dated June 9, 1885.

Application filed February 2, 1885. (No model.)

To all whom it may concern:

Be it known that I, ROBERT W. WHITEHURST, a citizen of the United States, residing at Norfolk, in the county of Norfolk and State of Virginia, have invented certain new and useful Improvements in Plows, of which the following is a specification.

My invention relates to an improvement in plows. The special feature comprising the invention consists of a standard having at its head or top part a side recess with bolt-holes for the attachment of the beam and provided at the rear lower part of the recess with means for adjusting the beam vertically.

The invention is illustrated in the accompanying drawings, in which Figure 1 is a side view of a plow-standard with beam attached, and showing the handles. Fig. 2 is a view of the head or top part without the beam. Fig. 3 is a cross-section on the line $x-x$ of head or top part of the standard and beam. Fig. 4 is a view of the wedge. Fig. 5 is a side view showing a modification in the construction of the means for adjusting the beam.

The letter A designates the iron standard of a plow. In the present instance the front of the standard is curved, as at b, to prevent weeds or trash from accumulating in front and under the beam and choking. A side recess, c, is formed at the head or top part of the standard by the upper flange, c', and lower flange, c'', which continues down at the rear part, k, and the pivot-bolt hole d passes laterally through the front of the head, and a vertical slot, e, for an adjusting-bolt through the back part of the head. The beam F, preferably of wood, sets in the side recess, and its thickness vertically must be less than the measurement between the upper and lower flanges, in order to leave above a space, c', for the movement of a beam.

The front bolt, d', serves to hold the beam, and also as a pivot when adjusting the beam. The flange which is at the rear part, k, of the side recess covers the end of the beam. The rear bolt, e', passes through the beam, and is thereby carried either up or down, according as the beam may be adjusted, and it occupies the vertical slot e. When the adjustment of the beam is changed, the rear bolt takes a higher or lower position in the slot. A portion of the beam

will always rest on the lower flange, c''. By this construction of standard head or top the beam may be firmly attached, and as the beam does not pass back of the standard a short beam may be used.

The means for adjusting the beam consist of an inclined seat or notch, g, at the rear lower part of the recess, and a slot, h, is in the side of the head, and has a pitch or incline 60 corresponding with that of the seat or notch. A wedge, I, occupies the notch g and sets on the incline, and a bolt, h', passes through the wedge and occupies the inclined slot and keeps the wedge in position. It will be seen 55 the wedge serves as a bearing for the rear extremity of the beam, and when the wedge is moved backward it is also raised by moving upon the inclined seat g. Any back movement, therefore, of the wedge serves to raise 70 the rear end, y, of the beam and to correspondingly depress its front end. A reverse movement of the wedge of course has an opposite effect. To adjust the beam, the rear bolt, e', of the beam and the bolt h' of the 75 wedge must both be loosened. The beam is then set at the desired vertical position, and the wedge brought to bear up against the beam. Then both bolts are tightened, whereupon the beam will be attached firmly.

In the drawings one side of the wedge and the inclined seat are shown serrated or corrugated. This is to prevent the wedge from slipping; but the serrations may be dispensed with, if desired. This construction of standard and means for adjustment of beam are applicable to both turn and cultivating plows, and also may be applied to standards which are not curved in front.

In Fig. 1 of the drawings the rear top part, 90 k, of the standard-head is shown curved; but this is immaterial. Instead of curved, this part may be square, as seen in Fig. 5. This latter figure also illustrates a modification in the means for adjusting the beam. Instead 95 of a wedge, a vertically-movable seat, l, is provided. This seat l has a serrated shank, m, which is in contact with a serrated vertical flange, n, on the standard. The shank is slotted, and a bolt, p, passes through the slot and 100 flange and retains the seat in any desired position. By raising or lowering the seat l the

beam will have its adjustment changed the same as though a wedge were used.

Having described my invention, I claim and desire to secure by Letters Patent of the 5 United States—

A plow-standard provided at the side of its head or top part with a beam-recess formed by an upper flange, c' , which continues down at the rear part, k , and is adapted to cover 10 the end of the beam, and a lower flange, c'' ,

and having a movable seat, substantially as described, at the rear lower part of said recess for adjusting the beam vertically, as set forth.

In testimony whereof I affix my signature 15 in presence of two witnesses.

ROBERT W. WHITEHURST.
